SPINNING TOP

Original Filed May 9, 1921

Inventor:
William A. Vinson
By Chapman & Ferguson
Attorneys:

UNITED STATES PATENT OFFICE.

WILLIAM A. VINSON, OF BALTIMORE, MARYLAND.

SPINNING TOP.

Application filed May 9, 1921, Serial No. 467,874. Renewed October 12, 1926.

This invention relates to improvements in spinning tops, and has for its object to provide a simple and cheap toy for amusement.

The invention consists of the novel construction and arrangement of the parts and combination of the parts hereinafter more fully set forth in the following specification and pointed out in detail in the appended claim.

10 In the accompanying drawing,

Figure 1 is a side elevation of my invention.

Figure 2 is a top plan view of Fig. 1.

Figure 3 is an end view of the bracket and tube.

Figure 4 is a plan view of the bracket before being bent.

Figure 5 is a side elevation of a modification of my invention.

20 Referring to the accompanying drawing forming part of this specification, 1 designates the top which in the present instance is formed of two sections of metal secured together at 2 the upper section being pro-

25 vided with a number of upwardly projecting blades or vanes 3 stamped therefrom and arranged symmetrically around the stem of the top at a radial distance less than the radius of the body of the top to give a greater velocity to the periphery of

30 said body than the velocity of the blades. Extending through the top 1 is a stem 4 for the purpose of holding the top in position in the bracket. The said bracket is formed of

35 the vertical piece 5 and two arms 7 and 8 extending at right angles thereto. The upper arm 7 is provided with an aperture 6 and the lower arm 8 is provided with a depression 9. Permanently secured to the

40 piece 5 of the bracket is a hollow tube 10 in line with the blades of the top.

The operation of the device is as follows:

45 The stem 4 of the top is inserted up through the aperture 6 and the lower end of the said stem rests in the depression 9 in

which position the blades 3 are in line with the tube 10. By blowing through the said tube 10 the air will strike the blades 3 and cause the top to revolve in the bracket 5. 50 The speed of the revolution of the top depends upon the force of air blown through the said tube 10. After the top has reached the desired velocity it can be removed from the bracket by a quick jerk of the tube 10 55 which will cause the said top to jump from the depression 9 and drop into the hand or other desired place.

In Fig. 5 I have shown a modification in which the upper section 11 of the top having blades 12 is secured to a wooden top 13.

While I have shown and described my invention being formed of two hollow sections it is obvious that same can be made of one piece or may be made solid as desired with 65 the blades projecting from the upper surface thereof.

Having thus described my invention what I claim is:

The combination of a bracket comprising 70 a vertical piece having two arms projecting at right angles thereto, one of which is provided with an aperture and the other with a depression near the free ends thereof, a spinning top comprising a body having a 75 stem projecting vertically through the center thereof and having one end projecting through said aperture and the other end resting in said depression, and a number of blades on the upper surface of the said body 80 and arranged symmetrically around the said stem at a radial distance less than the radius of said body to give a greater velocity to the periphery of said body than the velocity of the said blades, said top being 85 adapted to be thrown from the bracket while revolving and a hollow tube permanently secured to the vertical piece of the said bracket and in line with the said blades.

In testimony whereof I affix my signature.

WILLIAM A. VINSON.
